(57) CLAIM

The ornamental design for a woman's shoe, as shown and described.

DESCRIPTION

FIG. 1 is a perspective view of a woman's shoe showing our new design;

FIG. 2 is a left side view thereof;

FIG. 3 is a right side thereof;

FIG. 4 is a front end view thereof;

FIG. 5 is a back end view thereof; and,

FIG. 6 is a top plan view thereof.

The broken line showing of the sole is included for the purpose of illustrating and forms no part of the claimed design.

1 Claim, 4 Drawing Sheets
